BATH SPRAY

Charles T. Manville, Woodbury, and Paul S. Madsen, Bethany, Conn., assignors to The Seamless Rubber Company, New Haven, Conn., a corporation of Connecticut

Application January 11, 1945, Serial No. 572,300

5 Claims. (Cl. 299—141)

1

This invention relates to bath sprays of the type in which the spray head is connected with a water faucet by a flexible tube, the spray head or rose being manipulated by hand to direct the issuing spray of water.

One of the objects of our invention is to make manipulation much easier and more convenient than has been possible heretofore.

Another object is to provide a spray device in which the spray head can be controlled by hand very conveniently and effectively.

To these and other ends the invention consists in the novel features and combinations of parts to be hereinafter described and claimed.

In the accompanying drawing:

Fig. 1 is a bottom view of a bath spray embodying the invention;

Fig. 2 is an elevation, showing certain parts disclosed in Fig. 1;

Fig. 3 is an enlarged section on line 3—3 of Fig. 1;

Fig. 4 is a face view of the spray head, with the perforated metal plate removed; and

Fig. 5 is an exploded sectional view of the head, the section being taken on line 5—5 of Fig. 3.

The improved bath spray has a spray head indicated generally at 10, and a flexible rubber tube 11 attached to the head. A coupling device 12 of any suitable kind may be provided for securing the rubber tube to the water faucet. The present invention is concerned, among other things, with the structure of the head 10, and the means whereby it can be manipulated by hand to direct the spray of water. This is important in taking a shower bath, for example, where it is desirable to have the spray head under convenient control in the hand of the bather when applying the spray to the person's back and other parts of the body. While the structure of the spray head used is capable of variation, as will hereinafter appear, the particular structure shown by way of example will now be described.

The spray head or rose has its major portion constructed of suitable resilient plastic material, for example, compounded rubber or compounded rubber-like material, of a character to provide when cured a head having flexible elastic walls. The head is relatively shallow, having at one face a perforated metallic plate from which the spray issues. The inlet to the spray head is at one side, that is to say, in the peripheral wall of the head. It is here that the rubber tube such as 11 has communication with the interior of the head, and in connection with the struc-

2

ture adjacent the connection of the rubber tube to the head, an interior stiffening member is used for the purpose of providing in effect a laterally extending handle portion which greatly facilitates the manipulation of the spray head.

The spray head 10 shown in the drawing is a shallow round head having a cup-like body 13 of flexible rubber provided with a peripheral wall 14 in which is set a perforated metal plate 15. At one side of the head the rubber wall is formed to provide an inlet bore in an integral lateral boss 16. The rubber tube 11 is connected to this boss through an interior stiffening member 17, which may be conveniently made of hard rubber. The stiffening member is in the form of a tube having a bore 18, and a considerable portion of this tubular member is enclosed and held in tube 11, while a portion of tubular member 17 projecting out of tube 11 is used in making a connection of the tubular conduit structure to the spray head.

In the particular form shown, the tubular member 17 is provided at one extremity with a rigid collar portion 19 behind which is a portion 20 of less diameter, and behind the portion 20 is a rigid outstanding disk-like member 21. Behind the portion 21 the tubular member has a cylindrical portion 22, and behind 22 a rigid collar portion 23. By this construction there is provided a means for stiffening rubber tube 11 through a portion of its length, as well as an assembly in which the stiffening member is detachably held to and in the spray head on the one hand and the communicating tube on the other hand. The wall of the tube 11 engages over collar portion 23, and has its extremity disposed against one face of the member 21 in the manner shown, and the other face of member 21 is engaged by the end face 24 of boss 16, and the wall of the boss around its bore 25 is expanded over the collar portion 19. It is understood that the stiffening member forms a connection between the spray head and the flexible tube which ordinarily is not disassembled for a considerable length of time. The stiffening tube has, in locations adjacent its ends, portions for insertion into and connection with the head and the tube, respectively, with the spacing member 21 intervening, and a considerable portion of the stiffening tube being within and against the flexible tube to aid in providing a handle portion. Preferably the stiffening tube will have a slight bend therein so that the flexible tube will extend from the general plane of the spray head at a slight angle, as represented in Figs. 2 and 3.

The cup-shaped body member 13 of the spray head is preferably provided with a side wall which is substantially thicker than the top wall, as shown in Fig. 3, and this side wall may advantageously be rounded off, as shown at 26, at the mouth portion of the cup. The metal plate 15 is received in a groove in the side wall of the cup, and this plate preferably has a crowned or outwardly bulging portion 15' of substantially the diameter of the mouth of the cup. The plate also has a planar rim portion 27, and at right angles to the portion 27 an edge flange 28. The portions 27 and 28 are adapted to be received in an L-shaped groove 29 in the side wall of the cup, the groove 29 having a portion extending laterally into the side wall of the cup and a communicating groove portion to receive the portion 28 of the metal plate. As the side wall of the cup is elastic, it can be deformed in order to receive the perforated plate having the inwardly directed edge flange. The rubber of the side wall holds the plate firmly for the reason that portions of the rubber side wall prevent axial dislocation of the plate and also lateral dislocation thereof relatively to the rubber cup. After the spray plate has been installed, its flange 28 holds the mouth of the rubber cup against distortion from its normal round shape.

It is preferred to provide the metal plate with fine perforations throughout the portion within the rubber rim. Modification may be made in this respect, however, if desired. Nevertheless, inasmuch as the water entering the spray head comes in by way of bore 25 in boss 16, so as to tend to create a stream more or less parallel to the spray plate 15, it is desirable to provide means controlling the flow of water in the chamber of the head so that the water will be ejected from the different portions of the spraying surface in a uniform manner. For this purpose we provide the chamber interiorly with stream-controlling means whereby the body of water within the chamber is caused to pass through the perforated plate in a more uniform manner than would otherwise be the case. Were this means not used the tendency would be for the stream of water entering the head to be ejected from the head in greater part at the far side of the head. According to the present invention, however, we provide means whereby a certain amount of water in the chamber, before being ejected, is carried back in the general direction of the inlet, in order that the formation of a uniform spray can be brought about.

In the form shown, the stream-controlling means referred to includes flexible rubber walls that are advantageously integral with the structure of the rubber cup, said walls being three in number and of a character and arrangement very effective in producing the results above mentioned. In this particular form there are three walls 30, 31 and 32 formed integral with the top portion of the inverted rubber cup, the walls 30 and 31 being disposed at opposite sides, respectively, of the inlet bore 25 and leading to the left (Fig. 4) toward the opposite side of the cup, and the wall 32 being disposed between the walls 30 and 31 and leading from the left-hand side of the cup (Fig. 4) toward the right-hand side. These walls are approximately normal to the cup top, but they are obliquely disposed with respect to the general plane of the cup, as shown in Fig. 3. As shown in Fig. 3, the intermediate wall 32 extends from the left-hand side wall in an upward direction to a point indicated at 34,

said wall having a straight inclined lower edge 35. The walls 30 and 31, on the other hand, extend from the right (Figs. 3 and 4) to points 36, 37, and have straight lower edges 38. The walls 30 and 31 preferably diverge slightly from their bases adjacent the sides of the water inlet, as shown in Fig. 4.

In the operation of the device, the walls 30, 31 confine laterally, to an extent, the stream of water issuing into the chamber in the spray head. The intermediate wall 32 serves to divide the stream in a lengthwise direction so that its two parts are diverted toward opposite sides of the chamber and deflected by the chamber walls so as to be directed back toward the inlet. The water stream at each side of the wall 32 impinges against the curved wall of the chamber and is given a swirling movement so that a considerable amount of the water is thrown back to the region adjacent the inlet, thereby causing the spray to be ejected from the different parts of the perforated element in a substantially uniform manner.

It will be noted that the elastic top of the cup-shaped chamber is preferably formed on a shallow curve such as that illustrated in the drawing, the spray head itself being relatively shallow. The water-deflecting walls, each of which is joined to the inner surface of the slightly dished cup top and to a side wall, are provided with free or exposed edge portions preferably located at an angle to the general plane of the head, as shown.

In the operation of the improved bath spray the direction of the water spray can be readily controlled by grasping the relatively rigid controlling member projecting from the side of the head to which the flexible tube is connected, the flexible tube itself being stiffened through a substantial part of its length. The direction of the spray can be controlled by grasping the manipulating extension at any of a number of points near the head. The flexible tube may be stiffened throughout a length of say four inches, but this is mentioned only by way of example. The manipulating member can be very readily grasped, and where, for example, the person is taking a shower bath, the water can be easily and conveniently directed over the back of the person's neck and over all portions of the person's back and other parts of the body. A nicer and more convenient control is obtained than in the typical spray device where there is a connection between a flexible portion of tubing and the central part of the water chamber.

While only a single embodiment of the invention is shown, it will be understood that the invention can be embodied in various forms and that modifications and changes may be made without departure from the principles of the invention or the scope of the claims.

What we claim is:

1. A bath spray device comprising an inverted cup-shaped body member and a spray plate which form a water chamber, the body member being shallow and having a side wall and a slightly dished inner surface at the top, the water chamber having an inlet within the side wall of the body member, said inlet being formed as a conduit leading through a thickened portion of the side wall forming an extension on the body member, and deflecting means formed as a part of the body member tending to increase the uniformity of ejection of water from the spray plate, said last-named means including walls in-

tegrally joined to the top wall and side wall of the cup and disposed generally parallel to the incoming stream of water, two of which confine the entering stream at its sides and another which divides the stream lengthwise.

2. A bath spray device comprising an inverted cup-shaped body member and a spray plate which form a water chamber, the body member being shallow and having a side wall and a slightly dished inner surface at the top, the water chamber having an inlet within the side wall of the body member, said inlet being formed as a conduit leading through a thickened portion of the side wall forming an extension on the body member, and deflecting means formed as a part of the body member tending to increase the uniformity of ejection of water from the spray plate, said last-named means including walls integrally joined to the top wall and side wall of the cup and disposed generally parallel to the incoming stream of water, two of which confine the entering stream at its sides and another which divides the stream lengthwise, the last-mentioned wall being joined to the side wall of the cup at a point opposite the inlet and extending toward, but not to, the inlet, and the other two walls being joined to the side wall adjacent the respective sides of the inlet and extending longitudinally past the inner end of said further wall.

3. A bath spray device comprising an inverted cup-shaped body member of elastic material and a spray plate with which said body member forms a water chamber, said member having an inlet through its cylindrical side wall, the body member being relatively shallow and having a slightly dished top wall, the inlet to the water chamber being in a thickened portion of the side wall forming a lateral and outward extension on the body member, the spray plate having a flanged marginal portion set in the flexible side wall of the body member adjacent the mouth of the cup and preventing deformation of the mouth portion, and means including substantially straight walls joined to the top wall and side wall of the cup and extending substantially longitudinally of the entering water stream adjacent the top wall of the cup for inhibiting a localized ejection of water from the spray plate, two of which confine the stream as it enters and moves through a portion of the chamber diameter, and another extending from the portion of the side wall opposite the inlet and acting to divide the stream into two parts.

4. A bath spray device comprising an inverted cup-shaped body member of elastic material and having a cylindrical side wall and a spray plate with which said body member forms a water chamber, said member having an inlet through its side wall, the body member being relatively shallow and having a slightly dished top wall, and means for inhibiting a localized ejection of water from the spray plate including a pair of

walls integral with the top wall which confine the stream as it enters and moves through a portion of the chamber diameter and also including a third wall integral with the top wall extending from the portion of the side wall opposite the inlet to a point between the said two walls, the said pair of walls and the third wall having slanting lower edges directed inwardly and upwardly with reference to the cup side wall.

- 10 5. A bath spray device comprising an inverted cup-shaped body member of deformable flexible rubber which is shallow and has a slightly dished upper wall and a relatively thick side wall presenting a mouth, said side wall adjacent the mouth having an L-shaped groove, a spray plate having a flanged edge set in said groove and holding the mouth portion of the cup against deformation, said spray plate being provided substantially throughout its area with small perforations, the cup body having an inlet to the water chamber formed within a thickened portion of the side wall which provides a lateral outward extension on the body member, interior walls integral with the upper wall of the body member inhibiting localized ejection of water from the spray plate, and a nipple extending into said lateral extension of the side wall and having secured thereto a flexible supply tube, said nipple lying substantially in a median plane of the body member and being of appreciable length, and said lateral extension lying substantially in said median plane of the body member and together with said nipple providing a relatively stiff manipulating handle for the body member.
